UNITED STATES PATENT OFFICE.

JONATHAN O. FOWLER, JR., OF NEW YORK, N. Y.

ADVERTISING APPARATUS.

SPECIFICATION forming part of Letters Patent No. 257,684, dated May 9, 1882.

Application filed November 29, 1881. (Model.)

To all whom it may concern:

Be it known that I, JONATHAN O. FOWLER, Jr., of New York, in the county of New York and State of New York, have invented certain 5 Improvements in Advertising Apparatus, of which the following is a specification.

The object of this invention is to provide an apparatus whereby numerous signs, placards, or advertisements applied to a traveling apron 10 may be moved by a succession of long intermittent motions in one direction and then in the other; and to this end it consists in a novel construction and arrangement of mechanism hereinafter fully described.

I am aware that an apparatus has hitherto 15 been constructed in which a belt or apron was carried by a jolting motion of the apparatus in one direction by a series of short rapidly-succeeding movements, and then automatically 20 carried in an opposite direction in like manner. My apparatus differs therefrom in that my belt or apron is advanced by a succession of long movements separated from each other by considerable intervals of time, whereby each sign 25 or placard is exposed for a considerable period of time and the next then exposed by an instantaneous change.

Referring to the accompanying drawings, 30 Figure 1 represents a rear elevation of the apparatus; Fig. 2, an end elevation of the same; Fig. 3, a horizontal section on the line *x*-*x*, Figs. 1 and 2, looking downward, the teeth of the cam-wheel being developed or shown in plane projection; Fig. 4, a vertical cross-section on the line *y*-*y*, Fig. 3, developed or shown in a plane projection by dotted lines; Fig. 5, a view 35 illustrating the attachment of the pendulum by which the motion of the apparatus is controlled.

Referring to the drawings, A represents a 40 rigid rectangular frame designed to support and hold the various operating parts. This frame is provided at its opposite front corners with two upright rolls, B, to which are attached the opposite ends of a vertical apron or belt, C, the forward surface of which is provided with cards, signs, or advertising devices of any suitable character. By means of mechanism hereinafter described the rolls are turned first in 45 one direction and then in the other, thereby causing the belt to move transversely first up-

on one roll and then upon the other, thereby displaying the various cards successively at the front of the apparatus. The mechanism by which motion is imparted to the rolls is 55 clearly represented in the drawings.

At the top of the frame, in one end, is mounted an ordinary clock-train, E, consisting of a train of gear-wheels driven by means of a spring, G. The clock-train and spring, which may be of 60 any ordinary or suitable construction, are provided with a winding-arbor, H, of ordinary construction. The last or terminal pinion I of the clock-train has its shaft provided with a crank, K, connected by a pitman, L, to a crank-arm, 65 M, attached to a rock-shaft, provided with a pendulum, N, the pendulum serving through the connections described to control the motion of the clock-train and cause the same to run down slowly. On the main or winding arbor H of the clock-train I secure by a pawl and ratchet, or by any other equivalent device which will permit the arbor to be turned independently, a sprocket-wheel, O, which is connected 70 by a chain, P, with a corresponding wheel, Q, mounted on a horizontal shaft, R, in the base of the frame. The shaft R carries a large cam-wheel or drum, S, of the peculiar construction represented in the drawings. This wheel or drum is encircled by a series of inclined or beveled teeth, *a* and *a'*, formed or secured thereon. Around one half of the circumference the teeth *a* are beveled or inclined to the right, but around the remaining half they are inclined to the left, 75 as represented in Fig. 1, and also in Fig. 3. It will be seen that the bases or inner ends of the two series of teeth are in the same, or substantially the same, circumferential line, and that the two series extend right and left from this line, which, for the purpose of convenience, I 80 designate the "median line." At the point where the ends of the two series of teeth meet openings *b* are left between them, as plainly represented in Figs. 1 and 3. These openings are made to permit the passage of a pin, T, operated by the teeth to the right and left of the median line, as hereinafter described. To facilitate the passage of the pin, one tooth adjacent to each opening *b* is rounded on the rear side, 85 as shown at *c*, Fig. 1.

The pin T extends upward from a reciprocating block, U, which is sustained by rollers *d*,

traveling on the base-plate, and guided by means of two horizontal rods *e*, which are secured to the block and extended loosely through guides *f*, secured upon the base-plate. During 5 one-half of the revolution of cam-wheel *S* the teeth *a* act one after another against the pin *T*, forcing the pin, the block *U*, and the guide-rods *e* repeatedly toward the right hand, the pin and rods being moved gradually by each tooth to the 10 right of the median line until the pin passes the point of the same, whereupon the parts move backward quickly to the left to the base of the next tooth, this return movement being effected by means of a spring hereinafter described. As the cam-wheel *S* completes a half-revolution, and the teeth *a* have all acted successively upon the pin *T*, the opening *b* is brought opposite the pin, whereupon the pin passes through the same to the left in position 15 to be acted upon by the teeth *a'*, by which the pin and the rods connected therewith are repeatedly moved to the left, the pin now operating to the left of the median line. After the action of each tooth *a'* the pin is returned to 20 the base of the next tooth by a spring hereinafter described. As the cam-wheel completes the entire revolution the pin, reaching the end of the series of teeth *a'*, passes through the second opening, *b*, to the right, where it is 25 again acted upon by the first series of teeth *a*, as before described. It will thus be seen that by the continuous rotation of the cam-wheel the pin and the connected parts are first moved by a series of vibrations to the right of the 30 median line, and then given a like series of vibrations to the left of the median line, and so on alternately and repeatedly, this action occurring many times while the clock-train is 35 running down.

40 The springs by which the reciprocating rods are thrown to the right when under the action of one set of teeth, and then thrown to the left when under the action of the second set of teeth, are clearly represented in Figs. 1, 3, and 4. Two 45 horizontal arms, *W* and *W'*, are pivoted to the base-plate and connected respectively with independent spiral springs *x* and *x'*, attached to fixed studs on the base-plate, the springs acting to throw the ends of the arms *W* toward each 50 other. The movement of the spring-driven arms toward each other is limited by means of a fixed bar or stop-plate, *Y*, against the ends of which the arms come in contact. The two arms and springs operate alternately. The 55 rods *e* are provided on the back with two shoulders, *Z* *Z'*, as shown in Fig. 3, to engage with the ends of the spring-arms. During the action of the teeth *a*, when the parts are driven toward the right, the projection *Z'* of the rack-bar encounters the arm *W'* and forces the same to the right, and as each of the teeth *a* ceases its action the said arm forces the rods to the left. During this action the arm *W* rests 60 against the stop-plate *Y* and is inactive. 65 When, however, the teeth *a'* are brought into action so as to move the rod to the left, the stud *Z* of the rack-bar encounters the spring-arm

W, forcing the same to the left, so that the arm drives the rod back to the right as each of the teeth *a* ceases its action. During this operation the arm *W'* rests passively against the end of the stop *Y*. 70

To the reciprocating guide-rods *e*, I secure a horizontal rack-bar, *V*, which is carried by the movements of the bar first repeatedly to the right of a central line and then repeatedly to the left of said line. The rack-bar is designed to operate upon two wheels, *A'* and *B'*, alternately, the wheels being located, as shown in Fig. 3, in such position that when the rack-bar 80 is driven to the right by cam-teeth *a* it will operate upon the wheel *B'*, being carried away from the wheel *A'*, and that as the bar is moved to the left by the action of the teeth *a'* the bar will operate upon the wheel *A'*, being carried 85 out of contact with the wheel *B'*. The wheels *A'* and *B'* have a pawl-and-ratchet connection, as shown, with large gear-wheels *C'* and *D'*, respectively, these wheels both gearing into a third wheel, *E'*. The wheel *E'* is attached to 90 the axis of a large double pulley, *F'*, which is connected by two belts, *G'* and *H'*, with pulleys on the lower ends of the apron-carrying rolls *B*, for the purpose of turning the said rolls. 95

As shown in the drawings, the ratchet-teeth 100 of the respective wheels are faced in such directiuns that during the time the rack-bar is being operated to the right by the cam-teeth *a* it turns the gearing in such manner as to move the apron to the left, and that as 105 the rack-bar is moved to the left by the action of the cam-teeth *a'* it causes the apron to move to the right. In this way the continuously-revolving cam-wheel causes the apron to move first to the right and then to the left. The 110 ratchet-connection may be such that a positive motion will be imparted from the cam-teeth to the rolls; but it is preferred to face the teeth in the opposite direction, as represented in the drawings, so that during the time that 115 the rack-bar is being gradually moved by the cam-teeth the apron and its driving-gear will remain at rest. Under this arrangement the movement of the rolls and the driving-gear connected immediately therewith is effected by 120 the rack-bar during the time that the latter is being moved or returned under the action of the springs *x* *x'*. This arrangement is preferred for the reason that it permits each card or advertisement to remain at rest and exposed 125 to view for a period of time, and then causes the apron to be moved quickly to expose the next card. 130

While it is preferred to retain substantially the construction represented in the drawings, 125 it is obvious that the minor details of the apparatus may be varied in form or arrangement, provided there is no essential departure from the mode of action described and shown.

Having thus described my invention, what 130 I claim is—

1. The combination of the apron *C*, adapted to move on the supporting-rolls *B*, the clock-train, and the intermediate mechanism, sub-

stantially as described, whereby the clock-train is adapted to cause the apron to advance by a series of quick movements, with long intervals of rest, in one direction, and then in like manner in the opposite direction, whereby the cards or signs are displayed successively and one changed instantly to expose another.

2. In an advertising apparatus, the combination of a movable part or apron, C, a clock-train adapted to be propelled by a spring and intermediate mechanism, substantially as shown and described, whereby the belt is moved automatically and rapidly back and forth, the movement in each direction being effected by right and left hand cam-teeth upon a wheel, causing a succession of long quick movements of the apron, separated by longer intervals of rest, whereby each sign or placard is exposed at rest and an instantaneous change made to expose the next sign.

3. The combination of the driving-train, the cam-wheel provided with the right and left hand cam-teeth, the pin acted upon by said teeth, and devices, substantially such as described, connecting the pin with the movable display-surface.

4. The cam-wheel S, provided with the right and left hand cam-teeth, as described, in combination with a member reciprocated by the action of said teeth, and two springs arranged to operate alternately and force said member to the right and left.

5. The combination of the cam-wheel S, provided with right and left hand cam-teeth, as described, the reciprocating rack-bar V, connected with said wheel, and the two alternately-acting spring-arms W W'.

6. The combination of the cam-wheel having right and left hand teeth, the reciprocating rack-bar V, the springs W W', and the two driving-wheels connected by ratchet mechanism with pinions driven by the rack-bar, as shown and described.

7. The combination of the rolls B, the driving-pulleys with gear-wheels E', gear-wheels A', B', C', and D', with their ratchet mechanism, the reciprocating rack-bar V, the spring-arms W W', and the cam-wheel having teeth a a'.

8. In combination with the cam-wheel having right and left hand teeth, as described, the reciprocating bar, the two gear-wheels, A', and B', two spring-arms to operate upon said bar and stops for said arms, whereby they are caused to operate alternately on the rack-bar.

9. In combination with a member adapted for reciprocation, a cam-wheel provided with two series of cam-teeth, a and a', and passages b between said teeth, as described and shown.
